Primary Examiner—James M. Gandy*Assistant Examiner*—H. Baynham*Attorney, Agent, or Firm*—Jones & Askew[57] **CLAIM**

The ornamental design for a shelf support bracket, as shown and described.

DESCRIPTION

FIG. 1 is a perspective view of the bracket, viewed from a right, front, above perspective;
FIG. 2 is an enlarged left side elevational view with the opposite side being a mirror image;
FIG. 3 is an enlarged front plan view;
FIG. 4 is an enlarged rear plan view;
FIG. 5 is an enlarged top plan view; and,
FIG. 6 is an enlarged bottom plan view.
The broken line showing of a partial structure is for illustrative purposes only and forms no part of the claimed design.

FIG. 1

FIG. 2

FIG. 3**FIG. 4****FIG. 5****FIG. 6**
